UNITED STATES PATENT OFFICE.

MAX JAEGER, OF LONG ISLAND CITY, NEW YORK, ASSIGNOR TO ANCHOR CAP & CLOSURE CORPORATION, OF LONG ISLAND CITY, NEW YORK, A CORPORATION OF NEW YORK.

JAR-SEALING MACHINE.

Application filed April 17, 1922. Serial No. 553,898.

This invention relates to machines for forming hermetic side seals on glass containers or the like and comprises more specially a spinning mechanism adapted to 5 form the said seals.

The principal object of the present invention is the production of a spinning side seal forming machine with the mechanism thereof arranged to comprise unitary 10 groups.

A further object of the present invention is a side seal forming spinning machine wherein unsealed packages are fed to a spinning station where the package is retained 15 stationary during the spinning operation.

Another and important object of the present invention is a side seal spinning machine wherein the spinning head is adjustable to different heights during the operation of the 20 machine.

A still further and important object of the present invention is a spinning machine for forming hermetic seals on glass jars or the like and wherein cam controlled members 25 operate movements of the spinning rolls toward and from the axis of rotation of the spinning head to positively de-form the skirt of a suitable cap and force a gasket within the cap against the side wall of an incompressible container.

Another object of the present invention is a spinning machine for forming hermetic seals on glass jars, tumblers, or the like, and comprising a vertical driving shaft and a 30 spinning head vertically adjustable upon said driving shaft.

A still further object of the present invention is a machine of the character specified comprising a pair of concentric vertical 35 main shafts operatively connected to the spinning head in such manner that one of said shafts rotates the spinning elements while the other of said shafts reciprocates package holding and controlling devices.

Another object of the present invention is a machine of the character specified comprising a main frame carrying spinning 40 mechanism and devices for operating the same, in combination with an auxiliary frame carrying the power unit and transmission gearing in such manner that the power unit may be moved as an entity when desired.

Another object of the present invention is 45 a sealing machine of the character specified

provided with an integral package feed mechanism and an auxiliary frame carrying such package feed mechanism in such manner as to permit the package feed mechanism to be removed as an integral unit when 50 desired.

A further object of the present invention is a machine of the character specified comprising a main frame, a spinning head mounted on said main frame and being 55 adapted to be removed as an integral entity from the said main frame whereby said spinning head may be changed or replaced as desired.

A still further object of the present invention is the provision of rigidity to the operating parts by arranging parallel guides for the spinning head adjustment on one side of the machine main frame and a position clamp for drawing a cross head carrying the 70 spinning mechanism tightly against the parallel guides to rigidly maintain the spinning head in position directly over a spinning station.

A further object of the present invention 80 is to balance the driving constructions in such manner that the package feed devices are driven from the main shaft on the one side of the plane at which power is applied to the main shaft while the package clamp 85 and holding devices are driven from the other end of the main shaft and the spinning head is driven from a secondary main shaft.

Other and further objects of the invention will in part be obvious and will in part be 90 pointed out hereinafter in the specification following by reference to the accompanying drawings forming a part of this application and wherein like characters are used to indicate like parts throughout the several figures thereof.

It is realized that various types of mechanisms may be utilized in carrying out the present inventions and therefore it is desired that the specific disclosure herewith shall be 100 considered as illustrative and not in the limiting sense.

Figure 1 is a front elevation of the machine showing a portion of the driving mechanism in section and illustrating the 105 package feed frames broken away;

Figure 2 is a sectional view taken on section line 2-2 of Figure 1, and illustrates a vertical section through the machine.

Figure 3 is a section view taken on sec- 110

tion line 3—3 of Figs. 1 and 2, and illustrates a plan view of a portion of the driving mechanism in section;

Figure 4 is a view taken on line 4—4 of 5 Figure 1 and illustrates the feed head for positioning packages at the sealing station;

Figure 5 is a sectional view partially in elevation taken on line 5—5 of Figure 4 and illustrates the drive mechanism for the package feed device;

Figure 6 is an enlarged section of the spinning head similar to Figure 2 with the parts illustrated on a larger scale;

Figure 7 is a view through the top taken 15 on line 7—7 of Figure 6;

Figure 8 is a view taken on line 8—8 of 20 Figure 6 and illustrates the spinning rolls and mechanism for operating the same, with the rolls in an outward position to receive a package;

Figure 9 is a view similar to Figure 8, wherein the spinning rolls are shown moved inwardly to complete the spinning of a seal;

Figure 10 is a detail elevational view of 25 cap feed mechanism operated by the package feed device;

Figure 11 is a plan view taken on section line 11—11 of Figure 10;

Figure 12 is a detail view of the starting 30 and stopping lever; and

Figure 13 is a view taken on section line 13—13 of Figure 12.

Figure 14 illustrates the action of the 35 spinning rollers during the sealing operation.

Heretofore in the art it has been customary to form side seals on glass containers or the like by means of sealing chucks wherein the skirt of the cap was deformed through- 40 out its entire circumference simultaneously between under and upper jaws of a compression chuck which was operated by powerful mechanism to perform the deforming operation and compress the gasket. In this type 45 of machine it is necessary for very heavy pressure, amounting to several thousand pounds, to be exerted simultaneously over a relatively small area. This enormous pressure on the relatively small area on the 50 chucks tended to rapidly wear the chucks so that after a relatively short time the chucks were incapable of making as strong a seal as when the chucks were new. Furthermore, the simultaneous compression of 55 the entire gasket around the glass tumbler or similar container prevented any adjustment or yielding action of the gasket in the bead of the cap, with the result that glass which was defective by being out of round 60 or improperly annealed was often broken.

Furthermore the construction of such machines demanded that the parts be arranged to sustain very heavy forces and it was the custom to construct such machines as a complete entity so that a break or wear in any

part of the machine meant the disassembling of the entire machine sufficiently to reach and repair or replace the defective part.

Still further, in the chuck form of sealing machines the power required was very uneven and where a plurality of such machines were driven from a single power shaft this unevenness of power was multiplied when the machines were operating in synchronism. This produced very undesirable surges in the 75 power plant and in the line-shaft of the factory.

Another undesirable element sometimes encountered in machines of the chuck variety was the fact that the metal forming the skirt 80 of the cap often tended to wrinkle rather than flow as was desired to form the seal. This was due to the fact that the entire skirt of the cap was simultaneously being subjected to sealing forces, thereby preventing 85 the relief of stresses in any direction.

The present invention overcomes the difficulties of the known art by providing a machine wherein the sealing is adapted to be done by spinning rolls arranged in such 90 manner as to operate locally on a portion of the periphery of the bead of a suitable cap to deform the skirt and thereby form a side seal. In view of the fact that the sealing forces are rotary forces, and may be applied 95 gradually, there are no undesirable surges in the power required. Furthermore, since the sealing force is applied locally, a very much less power is required for the sealing operation than is necessary to operate a chuck 100 type of machine, because only a very small portion of the bead is under operation at one time. In view of the fact that the forces are locally applied to the bead of the skirt over the gasket there is an opportunity for 105 the metal in the skirt to yield in other directions and this obviates wrinkling of the seal and very greatly overcomes wear so that the same mechanism may be used for a relatively long period of time to form good 110 seals. Furthermore, since the sealing operation occurs locally, it is a very easy matter to adjust the position of the sealing rolls to compensate for wear. This is not possible 115 in a jaw chuck, where the jaws comprise continuous rings as has been common in the art.

The present invention also overcomes the difficulties of the known art by providing a construction wherein the machine is built in unity groups so that in case of any disablement of a member in a particular group repair or replacement may be accomplished easily by removing the group and substituting a new unit which may operate while the defective unit is being repaired. Furthermore the replacement of parts as units facilitates the change of the machine heads so that the machine may be quickly changed from one type of seal to another or from one size 125 to another.

Another difficulty in the prior art machines has been the fact that the adjustment of the machine to different height packages has been accomplished by raising or lowering the work supporting table. This in most cases required the machines to be hand fed because it was not feasible to move automatic feeding mechanisms each time the machine table was raised or lowered. The present machine obviates the difficulties of the known art in this particular by providing adjustments through which the spinning head may be raised or lowered without even stopping the running of the machine. This is an adjustment of great importance in the ordinary packing factory where one machine may from time to time be required to seal many different sizes and types of packages.

The machine of the present invention in a general outline comprises a main frame adapted to carry a power unit such as an electric motor geared to a suitable clutch and all mounted on an auxiliary frame with a drive gear carried by the drive shaft and extending beyond the frame. This mechanism is adapted to be manufactured, assembled, and dissembled as a unit, which greatly facilitates these operations. The main frame is provided with an upper and lower section, with the main drive gear mechanism in the lower section and with the upper section comprising guide members or supports for the spinning mechanism as will later be described. A pair of concentric hollow shafts are vertically mounted in the main frame and are adapted to be driven by the driving gears. The upper spinning head and operating devices are mounted in the upper part of the main frame and are vertically adjustable on guideways carried by the upper half of the main frame. The adjustment may be accomplished by a supporting screw shaft carrying a suitable hand wheel, the turning of which raises or lowers the spinning mechanism and a transverse clamp which is operative to clamp the spinning head frame tightly against the guides to maintain the parts very rigidly supported in any adjusted position. The spinning head which is carried on the spinning frame comprises spinning rolls mounted on cam controlled swinging arms. The spinning head rotates continuously, so long as the machine is running, around a stationary anvil adapted to engage the top of the bead of a cap. A stationary cam is carried by the anvil and is adapted to gradually move spinning rollers radially inward so that the spinning action is a compression action against the gasket. Prior to the beginning of the spinning action a container has been moved forward by the package transferring mechanism and as the container passes beneath the cap feed station a suitable cap having a bead with a gasket in the bead is dropped into position over the container. The container then moves forward and is stopped upon a spring supported table. The next operation is the lifting of this table by a suitable cam so that the head of the package is carried through a guiding funnel and the cap is brought into contact with the cap retaining head. This head is controlled by a cam mounted on one of the vertical hollow shafts and while the head recedes another cam on the same shaft descends until the anvil rests on the upper edge of the bead. As the anvil completes its downward movement it slightly compresses the spring beneath the supporting table and when this action begins the spinning rollers may move radially but not vertically, are gradually brought inward. The spinning action is a progressive action which begins at the lower part of the cap bead and gradually moves in an upward and inward direction, so far as the bead is concerned, due to the fact that the anvil is moving downward and the downward movement of the anvil carries the rotating spinning rolls inward. This action produces a very tight and efficient side seal and the cross-section of which may be varied to suit circumstances, but in the preferred form is of a general triangle shape.

From the foregoing it will be noted that the machine comprises a main frame upon which are mounted three auxiliary groups, namely, the driving mechanism, the spinning head, and the package feeding mechanism.

Driving mechanism.

The form of machine illustrated is provided with an individual drive mechanism illustrated in Figures 2 and 3. This drive mechanism comprises a base frame 1 adapted to be attached to the main frame of the machine and carries a supporting frame 2 on which an electric motor 4 is supported.

The drive shaft 5 of the motor carries a small gear 6 which meshes with a large gear 7 that carries driving plates of plate clutch 8. This large gear is loosely mounted upon a tubular drive shaft 9 and is supported against thrust by a ball-bearing 10. The tubular drive shaft 9 carries at the outer end a hand wheel 11 which may be utilized to turn the machine by hand for inspection or otherwise. A slidable collar 12 carries the driven plates of the plate clutch 8 and forms the pressure member by means of which the plates may be pressed together so as to transmit power from the motor to the main drive shaft. The clutch is operated by a bell crank 14 which is connected with a vertically extending link 15. The link 15 (see Figs. 12 and 13) passes through a collar pivoted in the arm 16 which is mounted

to rotate on the stub 17. A compression spring 18 tends to place the link 15 under tension when the hook 19 is locked over the dog 20 on the arm 16, as shown in Figure 12. When the operating handle 21 is moved toward the link 15 the extension 22 thereon engages a similar extension 24 on the arm 16, thereby causing the arm 16 to swing counter-clockwise to compress the spring 18 until the 10 hook 19 has dropped over the dog 20. This causes the connected parts to operate the slideable collar 12 to tightly clamp the plates of the clutch 8 together so that power from the motor shaft is transmitted to the main 15 drive shaft. When the operating handle is pulled away from the link 15 the release face 25 engages the dog 26 on the hook 19 and raises the hook 19 clear of the dog 20, thereby releasing the arm 16 and permitting it to 20 drop under the influence of the spring 18 and weight of the connected parts so that the clutch 8 is opened and the machine stops.

Referring now to Figures 2 and 3 the inner end of the tubular drive shaft is closed 25 by the plug 27 so that the shaft may be utilized to carry lubricant which is conveyed into the various bearings 28, 29 and 30 through small holes in the shaft 9. The inner end of the main drive shaft carries a 30 raw hide silent gear 31 adapted to mesh with other suitable gearings, as will be later explained. It will be noted that by removing the base 1 from the supporting frame and disconnecting the link 15, that the whole of 35 the power plant may be removed as a unit and replaced with such other drive mechanism as may be desirable or necessary either when making changes or for purposes of repair.

40 *Pedestal frame and vertical shaft.*

The main frame or pedestal frame and mechanism carried thereby is illustrated more specially in Figures 1, 2, and 3 to 45 which reference will now be made. The main base frame 101 carries the intermediate main frame 102, and the upper supporting main frame 103 and also forms the support for the frames 1 and 2 of the driving mechanism previously described. The base frame 101 is provided with a shelf 104 on which is mounted a lower gear frame 105. This gear frame carries a stub shaft 106 substantially 50 parallel with and in the same horizontal plane as the main drive shaft. A gear 107 on the stub shaft 106 is in mesh with the raw hide gear 31 on the main shaft. The stub shaft carries a worm 108 which is in mesh 55 with the worm wheel 109 on the vertical line shaft 110. This vertical line shaft is relatively slow moving and carries on each end certain cam members. The upper end of the line shaft 110 carries the spinning head cam 111 and the lower end carries table lift cam 112. This balances the torsion on the shaft. 60

It will be noted that the upper end of the vertical line shaft 110 is supported by a thrust bearing 113 which is sustained by the boss 114 on the supporting frame 103, and the lower end is supported in the bearing 115 70 carried by the gear frame 105. This vertical line shaft 110 is likewise hollow with the ends plugged in a suitable manner and thereby comprises a relatively large reservoir for lubricant which may feed through 75 openings (not shown) to the shaft bearings.

A bracket 116 is mounted upon the lower gear frame 105 substantially over the raw hide gear 31 and comprises a bearing for a short shaft 117 which carries on one end 80 a gear 118 in mesh with the raw hide gear 31. The other end of the short shaft 117 carries a bevelled gear 119 which meshes with a raw hide bevelled gear 120 that is mounted on the lower end of a tubular vertical main shaft 121 which surrounds and encloses a portion of the vertical line shaft 110. The main shaft 121 is supported at its lower end in a bearing 122 formed on the lower portion of the supporting frame 103 90 and at its upper end in a bearing 124 formed in the head frame 125 which is vertically movable relatively to the supporting frame 102. A raw hide gear 126 is mounted on the upper end of the main shaft 121 in a space 95 between the bearing 124 and the base of the housing 127 for the spinning head cam 111. The lower end of the spinning head cam is enlarged to revolve around a guiding collar 128 and the spinning head cam 111 is hollow. This spinning head cam is attached to the line shaft 110 by a slideable key-way connection and the raw hide gear 126 is similarly attached by a sliding key-way connection to the main shaft 121. A vertical 100 adjustment screw 129 extends through a portion of the head frame 125 and engages a nut 130 mounted between extensions on the head frame. The upper end of the vertical adjustment screw is provided with a hand wheel 131 so that the adjustment screw may be turned and the head frame raised or lowered in order that the spinning devices 105 will be at the right height to form hermetic seals, as will be later explained. During this raising or lowering movement of the head frame 125 the spinning head cam 111 and the raw hide gear 126 slide on their respective driving shafts and the main shaft 121 may have a telescopic movement through the guide collar 128 into the hollow space 110 in the spinning head cam 111. 115

Referring to Figure 1, it will be noted that guides 132 and 133 are provided on the face of the supporting frame and that the head frame extends outward over these guides. The back of the supporting frame is provided with a slot 134 (Figs. 2 and 6) through which a threaded member 136 extends and this member carries a clamping 125 130

wheel 137 which permits the head frame to be tightly clamped against the guides 132 and 133 so that the parts are rigidly held in adjusted positions. After the parts have been duly clamped the lock nut 138 is set to hold the parts securely in position.

Spinning head.

The spinning head mechanism which is illustrated more specially in Figures 1, 2, 6, 7, 8, 9, and 14 comprises vertical spinning shaft 201, carried in the head frame 125, and provided on its upper end with a gear 202 in mesh with the raw hide gear 126. The lower end of the spinning shaft 201 carries a rotating plate 203. This plate forms the support for the arms which carries the spinning rolls 204. These arms are formed in two parts 205 and 206. The part 205 carries the spinning roll 204 and the part 206 carries the guide roll 207. The arms 205 and 206 are associated with each other by means of a collar and sleeve construction consisting of a collar 206^a which is preferably integral with arm 206 and a sleeve 205^a which is preferably integral with arm 205. The collar on the arm 206 is clamped around the sleeve on the arm 205 by means of clamp bolts 208, and the composite element thus formed is pivoted to rotating plate 203 by a bolt 213. This construction permits an adjustment between the guide roll arm and the spinning roll arm so that the spinning head may be adjusted to accommodate caps of different diameters. A spinning anvil 209 is mounted on a tubular member 210 to which is connected the roller head 211 that carries the roller 212 which travels in the cam groove 214 in the spinning head cam 111. This roller head 211 comprises a guide which slides in guide-ways 215 (Fig. 1) provided on the housing 127 for the spinning head cam 111. A cap holder 216 is mounted on the lower end of the rod 217 which reciprocates through the member 210 and carries upon its upper end a roller head 218 which is provided with a roller 219 that cooperates with the upper cam groove 220 in the spinning head cam 111. The roller head 218 (see Figs. 1, 6, and 7) is adapted to slide in guide-ways 221 which are formed on the roller head 211 so that this member is effectively supported during its operative movements. The rotative plate 203 carries posts 222 (Figs. 8 and 9) which form supports for coil springs 224 that bear against the parts 206 of the spinning arms whereby the guide rolls 207 are normally positioned against a guide collar or templet 225 (see Figs. 2 and 6) which terminates in cone cam 226. The spinning head is enclosed in a casing 227 which is provided with a removable guide funnel 228. This guide funnel 228 is adapted to position the mouth of a jar with a cap thereon directly in the path

of the cap holder 216 so that the anvil 209 will properly engage the bead of the cap to enable the sealing operation to be completed. The casing 227 and housing 254 are each split in a plane parallel to the paper in Figure 1, and by removing cap screws 250, 251, 252, and 253, the entire spinning mechanism may be removed as a unit, including the spinning rolls, anvil, gear 202, and cam rolls 212 and 219.

70

75

Package feed mechanism.

The mechanism for feeding the packages is illustrated more specially in Figures 1, 2, 4, 5, 10 and 11.

80

Referring first to Figure 1, it will be noted that the vertical line shaft 110 at its lower end carries a gear 301 which is mounted just above the table lift cam 112. This gear 301 meshes with the corresponding gear 302 on the short vertical shaft 304, which shaft carries at its upper end a bevel gear 305 that meshes with bevel gear 306 shown in dotted lines in Figures 4 and 5. The bevel gear 306 is carried by a cross shaft 307 which is mounted in bearings in the table support frame 308. This cross shaft 307 carries a sprocket wheel 309 upon which is mounted the package feed chain 310. This package feed chain extends substantially the length of the feed table and passes over a sprocket wheel 311 near the outer end of the table. This sprocket wheel 311 is likewise mounted on a cross shaft 312 that is journaled in bearings near the outer end of the table frame. The cross shaft 312 carries a gear 314 which meshes with corresponding gear 315 on a short shaft 316 on which is mounted worm 317 (see Figs. 10 and 11). The worm 317 engages the worm gear 318 on the short vertical shaft 319 that carries the spacer plate 320, which is provided with package pockets 321. The opposite end of the cross shaft 312 is provided with a gear 322 that meshes with an idler gear 324 which drives a belt shaft 325. A pair of belt wheels 326 and 327 are mounted on the belt shaft and carry conveyor belts 328 and 329 that extend forwardly over pulleys 330 and 331 mounted on the idler shaft 332. A belt tightener 333 is provided to maintain the belts taut. The package feed chain 310 is provided at suitable intervals with package engaging lugs 334 which are spaced in timed relation with the package pockets 321 on the spacer plate 320. A suitable bed plate 335 is provided for the packages to slide upon and is formed with a slot 336 through which the package engaging lugs 334 travel. Adjustable guide-ways 337 are mounted on each side of the path of travel of the packages 339 to guide the packages while being moved under the influence of the package engaging lugs 334. It will be noted that the conveyor belts 328

85

90

95

100

105

110

115

120

125

130

and 329 are spaced apart on each side of the package feed chain 310 and the linear speed of the conveyor belts is substantially the same as the linear speed of the package feed chain. The drive for the spacer plate, the conveyor plates, and associated parts, comprises the package feed chain which is positively driven by the sprocket wheel 309 on the cross shaft 307. The cross shaft 307 (Figs. 1 and 4) is provided with a spiral gear 340 which meshes with the spiral gear on the connecting shaft 341. This connecting shaft 341 is also connected by means of spiral gears 342 and 344 (Fig. 11) with the cap feed shaft 345.

The cap feed (Figs. 1, 10, and 11) is operated by cam 346 mounted on the shaft 345 and cooperates with a roller 347 on the end of a lever arm 348. The opposite end of the lever arm is provided with a spring 349 which normally maintains the roller in contact with the cam and upwardly extending link 350 is connected to the lever arm adjacent the spring. The link 350 operates cap releasing mechanism 351 which feeds a single cap from the cap supply 352 and causes the fed cap to move downwardly to the cap applying mechanism 354, which is operated by the star wheel 355 (Fig. 11). This cap applying mechanism is described in general terms, only, for the reason that it forms the subject matter of a separate and independent application for patent S. N. 375,240, filed April 20, 1920. The hand wheels 356 are connected with short shafts 357 that carry crank arms 358, on which the track 359 for the package feed chain 310 is mounted so that this chain is vertically adjustable as may be required. This permits adjustment of the height to which fingers 334 project above the table, and permits adjustment to compensate for wear of track 359, and the chain 310. The track is secured in the adjusted position by means of set screws 390 which pass through the collar integral with the frame work and engage shafts 357 that carry the crank arms 358.

Table feed.

In the present machine when packages arrive at the end of the travel of the package feed conveyor the packages are removed from the conveyor and positioned upon a rising table directly beneath the spinning head so that packages may be raised into the active zone of the spinning mechanism and the seal formed accordingly. This table feed mechanism is illustrated more specially in Figures 1, 2, 4 and 5. The connecting shaft 341 is provided with a worm 401 (Fig. 2) which meshes with the worm wheel 402 that is mounted on vertical shaft 404. This vertical shaft carries a head 405 upon which are mounted two sets of fingers. Three of these fingers 406 are movable relatively to

the head and are controlled by a stationary cam 407 against rollers 408 carried by the finger control arms 409. These rollers 408 are held in engagement with the cam 407 by means of the springs 410. The intermediate fingers 411, while being adjustable on the head 405, are nevertheless stationary after the adjustment is made. As the head revolves the movable fingers 406 swing outwardly to pass the end of the package chain 310 and these fingers are mounted in timed relation with the package engaging lugs 334 so that any package being moved along by a lug 334 on the chain 310 will be engaged by a finger 406 and swept around over the bed plate 335 until the roller 408 drops from the cam face 412 of the stationary cam 407. When this happens the movable finger 406 loses control of the package and the package is left standing stationary. The next succeeding rigid finger 411 following picks up the package after intermediate operations have been performed thereon and carries the package onward.

When the package is left standing by the movable finger 406 it is positioned directly over the vertical movable table 414. This table (Figs. 2 and 4) is mounted upon a telescopic shaft 415 which is normally maintained in extended relation by means of the spring 416. This shaft is adjustably connected as at 417 with a slidable bar 418 mounted in suitable guide-ways 419 and that carries at its lower end a roller 420 which is adapted to follow the table lift groove 421 in the table lift cam 112. The parts are so timed that immediately after a package 339 has been left stationary on the table 414 by movable finger 406, the cam groove 421 becomes operative to lift the bar 418 and connected parts thereby raising the head of the package through the guide funnel 228 in the spinning head casing 227 thus bringing the cap into contact with the cap holder 216 which has been moved downwardly to meet the cap. After contact with the cap, the cap holder recedes and the anvil 209 moves downwardly until the rim of the anvil rests upon the bead of the cap. The continued downward movement of the anvil member causes the spinning rolls to be swung inwardly so that the rolls spin the bead against the side wall of the glass member of the package 339 and thus form a hermetic seal. As soon as the spinning operation is finished the table lift groove 421 in the cam 112 has reached such a position as to cause the package table to lower and when the package table has dropped to the position shown in Figure 2 a rigid finger 411 engages the package and sweeps it from the package lift table.

Regardless of the diameter of the packages being sealed it is desirable that they be centered with respect to the sealing mecha-

nism, and since the conveyor lugs 334 and the flights 406 and 411 engage the periphery of the containers, provision is made for advancing and retarding the timed movement of these parts with respect to the rest of the apparatus in order that they may properly position containers of different diameters. The advancement or retardation of the rigid flights 411 may be effected by manipulating nuts 481 and adjusting the flights individually. The corresponding adjustment of the movable flights 406 is accomplished by loosening nut 482 and shifting arm 483 thus adjusting the angular position of the stationary cam 407 which controls the operation of the movable flights. Advancement or retardation of the conveying lugs 334 is effected by manipulating bolts 360 and adjusting the angular position 20 of sprocket wheel 309.

Take-off mechanism.

The take-off mechanism for the sealed packages is shown more especially in Figures 25 1, 4, and 5 and comprises a conveyor belt 501, which is supported on driving pulley 502 and idler pulley 504. The driving pulley 502 is mounted upon a cross shaft 505 which carries a spiral gear 506 that is in engagement with a cooperative spiral gear 507 on the connecting shaft 341, which forms the drive connection for the driving shaft 505. The conveyor belt is provided with belt tightener 508 to maintain suitable tension of the belt, and which belt tightener is mounted upon the take-off frame 509 which is bolted to the main frame of the machine. Suitable package guides 510 are adjustably mounted adjacent the path of 30 the sealed packages in such manner that the packages will be maintained upon the conveyor belt, while being carried thereby. The packages come on to the conveyor belt from the lift table in spaced relation so that they 40 may be conveniently removed by operators or mechanism for packing for shipment.

Finished package.

Referring now more especially to Figure 50 14, when a package 339 with a cap 601 thereon is raised by the package table 414 and is engaged by the cap holder 216, the table continues to rise and the spinning anvil 209 descends. After the rim of the anvil 55 engages the top of the bead 602 the table continues to rise until the coil spring 416 is slightly under compression so that the bead 602 is lightly pressed against the rim of the anvil. This not only steadies the package 60 and provides an anvil to spin the bead against but it also holds the package stationary. The vertical spinning shaft 201 rotates continuously while the machine is running thereby carrying the spring rolls in

an orbital path around the axis of the shaft 65 201. The anvil continues to descend in the direction of the arrows A, and the guide rolls 207 engage the cone cam 226 thereby 70 swinging the roll carrying arms to bring the spinning rolls 204 into engagement with the lower part of the bead 602. As the anvil continues downwardly the motion described progresses and the spinning rolls have an effective inward and upward movement 75 against the bead 602 in a direction of the arrows B as well as the orbital movement, thereby spinning the metal in the bead of the cap inwardly and progressively compressing the gasket 604 so that a very tight 80 hermetic seal is formed against the side wall of the glass tumbler 605. After the anvil 209 has been retained in its lowermost position until the spinning rolls 204 have made such a predetermined number of revolutions on the bead 602 as are sufficient to 85 complete the seal, the anvil rises, and in rising the cone cam 226 moves upwardly relatively to the guide rolls 207 thereby causing the guide rolls to swing the roll carrying 90 arms in such manner as to remove the spinning rolls 204 from the bead 602 so that the package is left free to descend with the downward movement of the package table. When the package table reaches its lowermost position the package is removed therefrom in the manner previously described.

From the foregoing it will appear that the machine of the present invention is designed in unit groups of mechanism which when properly assembled form a completed whole adapted to automatically feed packages; place caps thereon; seal the caps on suitable containers; and then deliver the sealed containers in spaced relation for packing or labeling.

Having thus described my invention, what I claim is:

1. In a spinning machine, the combination of spinning rolls having orbital movement around a vertical axis, means for driving said spinning rolls, means for constricting said orbital movement to cause said spinning rolls to contract the bead of a suitable cap against the side wall of a suitable container to form a side seal, and devices for causing said cap to have a downward movement while said rolls are given an inward movement, said devices comprising a shaft and a cam for actuating said shaft.

2. In a spinning machine, the combination of spinning rolls having orbital movement around a vertical axis, means for driving said spinning rolls, means for constricting said orbital movement to cause said spinning rolls to contract the bead of a suitable cap against the side wall of a suitable container to form a side seal, and devices for causing said cap to have a downward movement

- while said rolls are given an inward movement, said devices comprising an anvil, a shaft associated with said anvil, and a cam for actuating said shaft.
5. 3. In a spinning mechanism for forming hermetic seals, a rotating main shaft, spinning mechanism comprising spinning rolls, said mechanism being adapted to be driven by said main shaft to revolve said spinning rolls in an orbital path for the spinning operation, a rotating line shaft, said main shaft and said line shaft being concentric, and means operated by the rotation of said line shaft to vary the size of the orbital path of 10 said spinning rolls.
4. In a spinning mechanism for forming hermetic seals, a rotating main shaft, spinning mechanism comprising spinning rolls, said mechanism being adapted to be driven 20 by said main shaft to revolve said spinning rolls in an orbital path for the spinning operation, a rotating line shaft and means operated by the rotation of said line shaft to vary the size of the orbital path of said 25 spinning rolls, and an anvil adapted to rest upon a suitable cap during the spinning operation.
5. In a spinning mechanism for forming hermetic seals, a main shaft, spinning mechanism including a spinning shaft and the spinning rolls, said spinning shaft being adapted to be driven by said main shaft to revolve the spinning rolls in an orbital path for the spinning operation, a line shaft, said 30 main shaft and said line shaft being concentric, means comprising cam members operated by said line shaft to vary the size of the orbital path of said spinning rolls, and an anvil adapted to rest upon a suitable cap 35 during the spinning operation.
6. In a spinning machine, a pivot, an arm comprising a sleeve cooperating with said pivot, a second arm comprising a collar clamped about said sleeve, a spinning roll 40 pivoted to one of said arms, a guide roll pivoted to the other of said arms, and a template cooperating with said guide roll.
7. In a spinning machine, a pivot, an arm comprising a sleeve cooperating with said pivot, a second arm comprising a collar 50 clamped about said sleeve and angularly adjustable relative thereto, a spinning roll pivoted to one of said arms, a guide roll pivoted to the other of said arms, and a template cooperating with said guide roll.
8. In a spinning machine, a pivot, an arm comprising a sleeve cooperating with said pivot, a second arm comprising a collar clamped about said sleeve, a spinning roll 55 pivoted to one of said arms, a guide roll pivoted to the other of said arms, a template, and means to maintain said guide roll in contact with said template.
9. A spinning machine comprising a frame; a spinning head carried by said frame and comprising spinning rolls; a power shaft; a pair of substantially vertical concentric shafts, both operatively associated with said power shaft to rotate at different speeds, and operative connections between 60 said concentric shafts and said spinning head, one of said shafts transmitting motion to effect rotation of the spinning rolls about the axis of the spinning head and the other shaft transmitting rotary motion to constrict 65 the orbital path of said spinning rolls.
10. A spinning machine comprising a frame, a spinning head carried by said frame and comprising spinning rolls and a spinning head shaft, a power shaft, a pair of 70 substantially vertically concentric shafts each operatively associated with said power shaft, means operatively connecting one of said concentric shafts with said spinning head shaft, a cam operatively connected with the other of said concentric shafts, and means controlled by said cam to constrict the orbital path of said spinning rolls.

MAX JAEGER.
